UNITED STATES PATENT OFFICE.

JOSEPH MARENGO AND AUGUST MARENGO, OF STOCKTON, CALIFORNIA.

SWIMMING BELT.

Application filed September 21, 1921. Serial No. 502,140.

To all whom it may concern:

Be it known that we, JOSEPH MARENGO and AUGUST MARENGO, citizens of the United States, residing at Stockton, county 5 of San Joaquin, State of California, have invented certain new and useful Improvements in Swimming Belts; and we do declare the following to be a full, clear, and exact description of the same, reference being had to the accompanying drawings, and to the characters of reference marked thereon, which form a part of this application.

This invention relates to improvements in aids to swimming, being particularly 15 intended for beginners, the principal object being to provide a buoyant belt so constructed that the wearer will be supported in the natural swimming position, that is, lying on his stomach in the water.

Another object is to provide a device of 20 this character which may be easily and quickly put on by the wearer, and when once so applied, cannot slip off, thus giving the wearer a feeling of absolute protection 25 and security while in the water.

A further object of the invention is to construct the belt in such a manner that while, as stated, it will adequately support 30 the wearer, it will not interfere in the slightest with the freedom of movement of his arms and legs, so that the entire efforts of 35 a beginner in the swimming art may be concentrated on acquiring the proper movements or strokes of the arms and legs, rather 40 than in merely keeping himself afloat.

A still further object is to provide a belt which may be readily folded up, and which will then occupy but a minimum of 45 space, and will, either when folded or in use, weigh but very little, so that the user 50 will not be tired either in transporting or wearing the belt.

Apart from its advantages for the purpose 55 above stated, the belt will also serve as an adequate life preserver in case of need, since as stated, it ordinarily occupies but little space, may be quickly put on, and will support the wearer for an indefinite period.

A further object of the invention is to 60 produce a simple and inexpensive device and yet one which will be exceedingly effective for the purposes for which it is designed.

These objects I accomplish by means of 65 such structure and relative arrangement of parts as will fully appear by a perusal of the following specification and claims.

Fig. 1 is a fanciful front outline of a man, showing our belt as worn.

Fig. 2 is a similar rear view.

Fig. 3 is a perspective view of the belt 60 detached, and with the shoulder straps removed.

Fig. 4 is a cross section of the belt taken on a line 4—4 of Fig. 2.

Referring now more particularly to the 65 characters of reference on the drawings, the numeral 1 denotes a length of non-stretchable belting of suitable width and preferably made of canvas or some similar material. Projecting from each end of the 70 member 1 are extensions 2 of equal length and made of some elastic material such as that used in the manufacture of suspenders and the like, which are arranged to overlap somewhat at their free ends and are there 75 provided with a co-operating and quick-fastening catch or hook member 3. The members 1 and 2 together are intended to be placed about the body of the wearer, a suitable distance above the waist and below the 80 arm pits, and with the member 1 in the back.

Shoulder strap members 4, also preferably of elastic material, are fastened to the back member 1, being adapted to be passed over the shoulders of the wearer and to be 85 fastened to the front belt portions 2 by catches 5 similar to the catch 3. These straps may however be omitted, as shown in Fig. 3.

Permanently secured to and on the outside 90 of the piece 1 is an air chamber 6, made of a fine quality of rubber, so as to hold air for an indefinite period without leaking, and yet be capable of folding or being doubled up into a small space without damage, and 95 to conform to the body of the wearer when in use.

An air valve 7 of any ordinary character is fitted into this chamber, so that air under 100 compression may readily be admitted thereto when desired, and as readily permitted to escape.

By reason of the inflexible portion of the belt to which the air chamber is fitted, the filling of the chamber with compressed air, 105 tending to stretch the same, has no such effect on the belt itself, the chamber-walls being thus only capable of expansion, transversely rather than longitudinally.

In this way, the belt will always fit the 110 wearer, regardless of the air pressure in the chamber, and the ends of the latter can thus

never extend to interfere with the arm movements of the swimmer.

The belt is intended primarily to be worn as illustrated, so as to support the wearer in the natural swimming position. Those desiring to do so however, may place the belt on in the reverse manner, in which case they will be supported in the position assumed by those who are "floating"—that is, 10 face upwardly.

It is evident of course that to suit all conditions, various lengths of belt and size of air chambers will have to be provided, but on account of the elastic extensions 2, one sized 15 belt may fit several persons of somewhat different build. Or if desired, one of the members 2, and the shoulder straps, may have slip-buckles, such as are employed on suspenders and garters.

20 The valve 7 is especially intended to be used in connection with a hand pump, but in the event that a pump is not carried or handy, and it is desired to inflate the chamber quickly, as in cases of ship wreck or 25 other emergency, we provide an additional mouth-valve 7^a, by means of which air may be forced into the chamber by the lung-power of the operator.

From the foregoing description it will be

readily seen that we have produced such a 30 device as substantially fulfills the objects of the invention as set forth herein.

While this specification sets forth in detail the present and preferred construction 35 of the device, still in practice such deviations from such detail may be resorted to as do not form a departure from the spirit of the invention, as defined by the appended claim.

Having thus described our invention, what we claim as new and useful and desire to 40 secure by Letters Patent, is:—

A swimming belt having its end portions of elastic material but the portion therebetween of non-elastic material, said ends having co-operative fastening means, and a pliable air chamber member adapted to receive air under compression mounted on the non-elastic portion of the belt, whereby when placed about the body of the wearer the belt will accommodate itself to different sizes of 45 bodies but the filling of the air chamber with compressed air will not cause a lengthening 50 of the belt.

In testimony whereof we affix our signatures.

JOSEPH MARENKO.
AUGUST MARENKO.
